ATTORNEY

UNITED STATES PATENT OFFICE

AUGUST W. VIEHMANN, OF BELLEVILLE, ILLINOIS

AUTOMATIC SCREEN CLEANER

Application filed March 22, 1930. Serial No. 438,199.

This invention relates to new and useful improvements in automatic screen cleaners and has for its primary object the provision of a device of the above stated character to prevent clogging of the screen employed for grading or separating materials of different sizes such as coal, stones, gravel, sand, etc.

Another object of this invention is the provision of pivoted pendulums to jar or vibrate the screen during the reciprocatory movement thereof to prevent the fine grade of material from clogging the openings in the screen.

A further object of this invention is the provision of an automatic screen cleaner of the above stated character, which shall be simple, durable, and efficient, and which may be manufactured and sold at a comparatively low cost.

With these and other objects in view as will become more apparent as the description proceeds, the invention consists in certain novel features of construction and arrangement of parts, as will be hereinafter more fully described and claimed.

For a complete understanding of my invention reference is to be had to the following description and accompanying drawing in which:

Figure 1 is a side elevation partly in section illustrating an automatic screen cleaner constructed in accordance with my invention.

Figure 2 is an end elevation illustrating the same.

Referring in detail to the drawing, the numeral 1 indicates a screen of a well known construction for separating materials of different sizes and which is adapted to have the material pass thereover, and during the re-

ciprocation of the screen the finer material to pass through openings of the screen and thereby be separated or segregated from the coarser material.

The material to be graded is fed over the screen 2, the material of certain sizes passing through the openings in the screen 2 on to the screen 3 while the coarser material passes to a pile or container and the material on the screen 3 is again separated, the finer passing on to the bottom 4 while the second

grade of material delivers into another pile or container from the bottom 4. The materials passing through the openings in the screens 2 and 3 frequently clog the openings and render the screens inefficient in their operation, and to overcome this objection my invention is applied to the bottom 4 and operates through openings 5 in said bottom to jar or vibrate the screens during their reciprocatory motion to cause any material clogging the openings to pass therefrom.

A bracket 6 is secured to the bottom 4 of the screen 1 between the openings 5 and carries the wrist pin 7 on which a pendulum 8 is journaled. The pendulum includes a shank 9, the upper end having an opening to receive the wrist pin and its lower portion provided with a series of openings 10 any one of which is to receive a set screw 11 carried by a counter balance weight 12 to permit the weight to be adjusted relatively to the shank 9. A head 13 is formed on the shank 9 adjacent the pivoted end thereof, and includes a pair of arcuate shaped arms 14 disposed in opposite directions from the shank 9 and extending through the openings 5 of the bottom 4. The head 13 is substantially semi-circular in shape and during the reciprocation of the screen 1, the shank 9 is swung on the wrist pin 7 in a backward and forward manner to cause the ends of the head 13 to strike the screen 3 and vibrate the latter to cause material that may clog the openings to pass therefrom and thereby maintain the screen in a condition to efficiently separate or grade the finer material. The counter-balance weight 12 being adjustable on the shank 9 permits the force of the head 13 against the screen to be varied if desired.

While I have shown and described the preferred embodiment of my invention, it will be understood that minor changes in construction, combination and arrangement of parts may be made without departing from the spirit and scope of the invention as claimed.

Having thus described my invention what I claim is:

An automatic screen cleaner including a screening element and a reciprocating frame

therefor having spaced slots in the bottom wall, a bracket secured to the bottom wall between the slots, a shank having one end pivoted to the bracket and provided with spaced openings adjacent the other end thereof, a weight slideable on said shank, a fastener carried by the weight and adapted to extend into any one of the openings to adjustably secure the weight to the shank, and a pair of oppositely disposed arcuate shaped arms formed integrally at one of their ends with the shank adjacent the pivot and extending through the slots to permit the other ends thereof to alternately strike against the screening element during the reciprocation of the frame.

In testimony whereof I affix my signature.
AUGUST W. VIEHMANN.
